UNITED STATES PATENT OFFICE.

EDMUND C. MORGAN, OF CHICAGO, ILLINOIS.

MINING-MACHINE.

1,328,755.

Specification of Letters Patent. Patented Jan. 20, 1920.

Application filed February 10, 1918. Serial No. 747,250.

To all whom it may concern:

Be it known that I, EDMUND C. MORGAN, a citizen of the United States, residing in the city of Chicago, county of Cook, and 5 State of Illinois, have invented certain new and useful Improvements in Mining-Machines, of which the following is a specification.

My invention relates to mining machines 10 of the short wall type, in which ropes or cables are used for moving the machines to their proper locations and for feeding them along during operation. Heretofore, such mining machines have been provided with 15 feeding mechanism and guiding apparatus comprising winding drums of such small diameter that ropes or cables of small cross-sectional area have to be used to secure sufficient flexibility to properly perform their 20 functions and to prevent their being broken or injured within a very short period of use. In such instances, where heavy duty has been required of the feeding mechanism, heavy chains have been used, but these are 25 cumbersome and inefficient, and it is difficult for the operators to move them about from place to place according to the points of anchorage. To overcome the objections 30 of the small drum rope or cable winding mechanism of the feeding and guiding apparatus, and to overcome the objections to heavy chains, I have provided improved 35 rope drum feeding mechanism and rope drum guiding apparatus, wherein the winding drums are of large diameter, preferably of approximately the same diameter as the width of the mining machine. By reason of the provision of the drums of large 40 diameter, the ropes or cables are only slightly bent, thereby prolonging the life of the rope or cable considerably. The construction being such that the ropes or cables are only slightly bent, such ropes or cables need not be very flexible and, therefore, may 45 be made of much coarser strands than the ropes on the mining machines having small winding drums. Therefore, the ropes or cables on my improved apparatus, embodying the large winding drums, may be used 50 freely without danger of breaking or becoming injured, which increases the efficiency of the operation of the mining machine because avoiding delays due to the breaking of the rope or delays in handling 55 the rope when it is partially broken. It will, therefore, be evident that the particu-

lar object of the invention is to provide rope drum feeding mechanism and rope drum guiding apparatus in which stronger and less expensive ropes may be used, which 60 will also be more durable and efficient, and render the operation of the mining machine more efficient.

A further object of my invention is the provision of large rope drums approximately equal in diameter to the width of the mining machine, so that the ropes extending from the drums may pass along the side of the mining machine either forwardly or rearwardly to anchorages, as well as laterally from the mining machine, so that the rope drums may be used for pulling the machines longitudinally forward or longitudinally rearward as well as laterally for 65 feeding purposes.

Another object of the invention is the provision of freely detachable rope guides adapted to be connected to the cutter-bar of the mining machine when the machine is to be pulled longitudinally forward, or connected to the rear portion of the mining machine on the other side when the mining machine is to be pulled longitudinally toward the rear, the rope pulley guide being 80 connected to the rope between the anchorage 85 and the rope drum so as to swerve the mining machine toward the anchorage and then guide the mining machine toward the anchorage rectilinearly.

Another object of the invention is the 90 provision of a U-shaped cutter-frame detachably connected to an elongated cutter-bar or frame, whereby said U-shaped cutter guide frame, after becoming worn, may be removed and replaced by a new guide frame, 95 while the elongated cutter-bar or frame remains rigidly connected to the main frame of the mining machine.

Other objects of the invention will appear more fully hereinafter.

Referring to the accompanying drawings,

Figure 1 represents the side elevation of my improved rope mining machine;

Fig. 2 is a plan view of the mining ma- 105 chine;

Fig. 3 is a sectional longitudinal elevation on the line 3—3 of Fig. 2;

Fig. 4 is a rear view of the mining ma- 110 chine;

Fig. 5 is a plan view of the truck gearing;

Fig. 6 is a sectional plan view of a portion

of the gearing of the machine taken on the line 6—6 of Fig. 3, and represents the speed change gears for the large rope drum;

Fig. 7 is a fragmentary view showing the modifications that may be used in place of a spring for rewinding the smaller rope;

Fig. 8, to the right and above Fig. 2, is a section of a portion of Fig. 2 on the line 8—8, looking in the direction of the arrows, 10 and represents the chain cutter frame and the means for supporting the same;

Fig. 9, below and to the right of Fig. 2, is a device for connection to the machine and association with the ropes to effect proper 15 movement of the machine as a whole;

Fig. 10, above and to the right of Fig. 1, is a diagrammatic illustration of the mining machine making a cut across the face of the wall of the coal or the material being mined;

Fig. 11, below and to the right of Fig. 1, is a diagram illustrating the pulling of the mining machine toward the truck on which it is mounted for transportation to new 25 locations;

Fig. 12, to the right and above Fig. 3, diagrammatically represents the mining machine starting its cutting operation along the face of the wall of the mine;

Fig. 13, below and to the right of Fig. 3, represents diagrammatically the unloading of the mining machine and pulling the same to the point where the cutting operation is to begin;

Fig. 14 represents a plan view of the frame of the mining machine stripped of all its parts except the rope drums and the chain cutter frame and supports;

Fig. 15 represents the right hand end view 40 of Fig. 14 and includes diagrammatically a portion of the gearing shown in the upper part of the frame on Fig. 3;

Fig. 16 represents a side view of Fig. 14; and

Fig. 17 is a fragmentary view showing devices for locking the drums together.

It will be seen by referring particularly to Fig. 3, that the flat bottom mining machine is mounted on the platform 2 of a truck, which is mounted on the wheels 3, the latter being adapted to move on suitable rails of a mine track. On the axle 18 of the truck is mounted a bevel gear 5 which is in mesh with the bevel gear 6, the latter being mounted on the shaft 7 which extends to the forward gearing which is associated with the forward axle. Near the gear wheel 6 is the worm wheel 8, which meshes with the worm 9. It is understood that the gearing associated with the forward axle is similar to the gears 5 and 6.

A suitable bracket 10 supports the bearings for the shaft 7 to which the worm wheel 8 is keyed. The bracket 10 also affords a bearing for the end hubs 11 and 12

of the worm 9. The bracket 10 is fastened to the under surface of the platform 2 of the truck. Extending longitudinally through the center of the worm 11 is a clutch coupling pin 13 having preferably a 70 square cross section, a flat surface at its upper end and a rounded surface 14 at its lower end. There is also a lower extension 15 which has an enlargement 16, the upper surface of which is rounded so as to minimize friction when engaged by the lever arm 17 which extends downwardly from the axle 18 and forms an arm of a bell crank lever, the other arm of which comprises the handle 19. The pin 15 extends through an 75 opening in the forward lower end of the lever 17. When the latch mechanism 20 is actuated to release the handle 19 from the fixed notch drum 21, the lever 17 may be lifted provided the bottom 1 of the mining 80 machine is in proper position. This proper position is determined in this instance by the rear portion of the frame abutting against the cross piece 22 on the rear upper surface of the truck platform 2. When the 85 mining machine is in proper position on the platform of the truck, the socket 23 at the lower end of the power driven shaft 24 will be directly over the clutch coupling pin 13. When the latter is moved upwardly 90 into the socket 23, it may be held in such position by the latch mechanism 20, 21. By reason of the enlargement 16, the clutch coupling pin will always be maintained in proper position and can be moved down 95 positively when it is to be released from the socket 23.

In order to hold the mining machine in place on the truck, the rope indicated by dotted lines 28 in Fig. 2 is provided with a 105 hook 25 for engagement with an eye 26 at the upper end of the bracket 27 which is fixed rigidly to the cross piece 22. By referring to Fig. 4, it will be seen that the vertical bracket 27 is located at one end of the cross piece 22 because the rope and the hook and eye connection are to be used principally for moving the machine onto the truck. In order to bring the mining machine more accurately and definitely to the 110 position on the truck where the socket 23 will be directly over the clutch coupling pin 13, longitudinal guide strips 29, 29 may be provided, as shown in Figs. 2 and 4. These 115 guide strips are located on the upper surface of the truck and engage the lateral surfaces of the mining machine frame to guide it longitudinally on the truck so that when the mining machine abuts against the cross piece 22 the socket 23 will be directly above 120 the clutch coupling pin 13. Now, whenever the electric motor 30 is operated in one direction or the other, its beveled pinion 31 will transmit motion to the large bevel gear 32 which in turn will transmit motion to 125 130

the vertical shaft 24, since the large gear 32 is keyed to said shaft. Therefore, when the motor is operating and the clutch coupling pin 13 is moved into the socket 23, motion 5 will be transmitted to the truck wheels to effect transportation of the truck and the mining machine in one direction or the other along the mine track depending on the direction in which the motor has been operated. The motor may be provided with a controller box which is diagrammatically illustrated at 33 in Figs. 1 and 2. The motor may be reversed by operating the lever 138, and started and regulated in speed by 10 operating the lever 141.

Projecting from the forward lower portion of the frame of the mining machine and rigidly connected to said frame is a cutter frame support 34, shown in section in Fig. 20 and in plan in Fig. 14. A section on line 8—8 of Fig. 2, looking in the direction of the arrows, is shown in Fig. 8. The cutter frame 35 has an interlocking connection at 36, 36, with the lateral faces of the longitudinal extension 34. The cutter frame, as shown in Fig. 14, comprises two lateral parts which are the interlocking members, and a forward semi-circular portion 37, which is bolted to the lateral interlocking members 25 at 38, 38. Connected rigidly to the inner face of the semi-circular portion 37 by means of the lock nut 139 (Fig. 3), is a screw-threaded rod 39 which extends rearwardly through the cross piece 40 at the outer end of 30 the cutter head 34. The screw-threaded rod 39 may extend some distance into the outer end of the cutter head 34, as shown by the dotted line 41, so as to secure a greater 35 latitude of movement of the chain cutter frame 35. On the screw-threaded shaft 39 are the nuts 42 and 43, one being located on one side of the cross piece 40 and the other on the other side thereof. When the nut 42 is moved rearwardly and the nut 43 40 tightened up, the chain cutter frame may be moved outwardly to increase the tension of the chain 44 (see Figs. 2 and 14). This structure, including the elongated bar 34 connected rigidly to the framework and the 45 U-shaped detachable chain guide frame 35 adjustable longitudinally on the lateral edges of the bar 34, together with the adjusting mechanism mounted at the outer end of the bar 34, I have described and claimed 50 in my copending application Serial No. 196,294, filed October 12, 1917, for an improvement in mining machines. The chain cutter is mounted on sprockets which run in interlocking grooves 45, 45 in the guide 55 frames or chain cutter frames 35, 35 and the forward circular portion or frame 37 (see Fig. 2). The sprocket chain carries a plurality of sockets 46, in which are held the cutters 48 by means of the set screws 49, as 60 shown in Fig. 2.

It should be particularly noted that the cutter-head 34 is rigidly connected to the supporting frame of the mining machine; in Fig. 3 this cutter-head 34 is shown integral with the frame 1. By referring to Fig. 70

14, it will be seen that the circular portion 37, together with the tapering side portions 35, constitutes a U-shaped guide frame or chain cutter frame having an interlocking connection at 36 with the cutter-head 34, as 75 shown in Fig. 8. This U-shaped frame 35, 37 is removable and therefore when it becomes worn it may be replaced by a new U-shaped frame, while the cutter-head 34 remains intact. This arrangement also lessens the cost of construction, because the cutter-head 34 may be made of cast iron whereas the parts which take the wear of the traveling chain cutter must be made of such material as steel. The arrangement is 80 therefore of advantage not only in the first cost of construction, but also as to the expense of maintenance. The U-shaped frame is purposely made elongated so that it may take the wear of the chain throughout the 85 entire run of the chain where such wear will occur. The sides of the guide frame 35 at the rear ends thereof are in alinement with the periphery of the sprocket wheel, as shown in Fig. 2. The cutter-chain is therefore supported entirely by the sprocket wheel 50 and the detachable elongated 90 U-shaped guide cutter-frame 35, 37. On account of the removability of the U-shaped frame 35, 37 it may be held in adjusted position relative to the elongated cutter-head 34 so as to adjust the slack in the cutter-chain. 95

The chain cutter extends rearwardly around the sprocket wheel 50, which is 100 mounted loosely on the vertical shaft 24 (Fig. 3), but its upper surface is provided with clutch teeth so that when the clutch 51 is moved down, driving connection will be established, the clutch 51 being splined to the shaft 24. The clutch 51 is provided with a central circumferential groove which is engaged by a yoke 52, the latter being mounted on the rock shaft 53. This rock 105 shaft 53 which carries the yoke 52 is mounted in bearing 54, 54, as shown in the dotted lines in Fig. 2. At one end of the rock shaft 53 is connected an actuating lever 55 which extends upwardly to an opening 56 in the upper horizontal portion of the frame 110 of the mining machine as shown in Figs. 1 and 2. Therefore, when the manual lever 55 is actuated to the right, as viewed in Fig. 1, the clutch 51 will be moved down into engagement with the teeth on the upper side 115 of the sprocket 50; if the motor is now in operation, motion will be transmitted to the cutter chain through the pinion 31, gear 32, shaft 24, clutch 51 and sprocket 50. The 120 motor should be started in the proper direc- 130

tion according to the position of the cutters 48.

Referring now to Fig. 3, it will be seen that a horizontal support 57 is provided for the various parts associated with the vertical power driven shaft 24. This support 57 is rigidly connected to the inner front and rear walls of the main frame of the mining machine, as indicated at 58, 58. At 10 the central portion of the horizontal support is an annular depression to receive the circular plate 59, which loosely surrounds a central portion of the vertical shaft 24 and serves as a bearing for the worm 60 which is keyed to the shaft 24 above the bearing plate 59. Keyed to the hub sleeve 61 of the large disk gear 32 is a bevel gear 62 which meshes with a bevel gear 63.

In Fig. 6, which is a plan sectional view 20 of a portion of Fig. 3 on the line 6—6, is shown the shaft 24, the worm 60 keyed thereto and the gear 63 which, as shown in Fig. 3, is always in mesh with the bevel gear wheel 62. The plate 59 is provided with a bracket 25 arm 64 for supporting the bearing 65 in which is journaled one end of the short shaft 66, the other end of which is journaled in the bearing 67 which is supported directly above and on the plate 59. The plate 59 is 30 cut away at 68 to permit free rotation of the bevel gear 63. To the bevel gear 63 is connected the worm 69, which is mounted on the shaft 66. Preferably, the short shaft 66 is securely fastened to the end supports and 35 the gear 63 and the worm 69 rigidly connected together and both loosely journaled on the shaft 66.

Meshing with the vertical worm 60 is a worm wheel 70, which is keyed to the shaft 40 71, one end of which is journaled in the bearing 72 which is carried by the bracket 73, mounted on the plate 59. The shaft 71 on the side of the worm wheel 70 opposite the bearing 72 is somewhat enlarged, as shown 45 at 74, and is journaled in the long bearing 75 which is supported by the bracket 76, mounted on the plate 59. To the outer end of the shaft 74 is keyed a worm 77. Therefore, whenever the shaft 24 is rotated the worm 50 60 and the worm wheel 70 will be operated to turn the worm 77.

To the forward inner wall of the main frame of the mining machine at 58 is rigidly connected a horizontal bracket 78, which 55 carries a bearing 79 for the auxiliary shaft 80 which is shown mounted in vertical position in Fig. 3. Keyed to the upper portion of shaft 80 below the bearing 79 is a worm wheel 81. The lower end of the vertical 60 shaft 80 extends into a recess 82 which forms a step bearing for said shaft, and also a journal bearing.

By referring to Fig. 2, it will be seen that 65 a manually operable lever 83 is located on the upper side of the main frame of the min-

ing machine. This lever is connected to a vertical rock shaft 84 which is mounted in bearings 85 and 86, as shown in Fig. 1. To the lower end of the vertical rock shaft 84 is secured a lever arm 87 to which is pivoted 70 one end of the link 88, the other end of which is pivoted at 89 to the lever arm 90 which is a horizontal plate or bracket extending from the bracket 76, as shown in Figs. 1 and 6. It will now be evident that 75 when the manual lever 83 is actuated the lever arm 90 may be shifted in one direction or the other and thus oscillate the plate 59 and the parts carried thereby. This will throw either the worm 69 or the worm 77 80 into engagement with the worm wheel 81. The gearing is such that when the worm 69 is thrown into engagement with the worm wheel 81 the shaft 80 can be rotated at a comparatively high rate of speed, that is, as 85 compared with the speed produced by throwing the gear 77 into mesh with the worm wheel 81. The gearing ratio when the worm 69 is in mesh with the worm wheel 81 is such as is consistent with the greatest speed 90 that can be used in practice for moving the entire mining machine to or from its work, or from place to place in the mine, or to and from the truck.

It will be seen, by referring to Figs. 3 and 95 6, that when the worm 69 is in mesh with the worm wheel 81 and the electric motor 100 is actuated, motion will be transmitted by means of the gears 31, 32, 62, 63, worm 69 and worm wheel 81 to the vertical shaft 80. When the worm 77 is thrown into engagement 105 with the worm wheel 81 and the motor is operated, motion will be transmitted to the vertical shaft 80 by means of the gears 31, 32, 60, 70, 77 and 81. It will be seen, 110 however, that because of the worm gearing 60, 70, the shaft 80 will be rotated at a much lower rate of speed than when the gear 69 meshes with gear 81. As will be hereinafter explained, when a very slow feed of the machine is desired during the cutting operation, the worm 77 is brought into play, but when the machine is to be moved about without loss of time then the worm 69 is brought into play to effect a much quicker operation. 115

The rope drum mechanism of my improved mining machine will now be described. Depending from the horizontal supporting plate 57, are a plurality of brackets 91 which receive the lower ends of 120 the pins 92, the heads 93 of which rest on the upper surface of the plate 57. On these pins 92 are journaled the circumferentially grooved anti-friction rollers or disks 94 and 95, as shown in Fig. 2 in dotted lines and in 125 Fig. 3 in full lines. The circumferential grooves of these disks receive the annular flanges 96 and 97 of the rope drums 98 and 99, respectively. It will be seen that by reason of this construction the drums 98 130

and 99 are supported out of contact with each other and in contact with no other parts, except that the flanges 96 and 97 of the drums rest in the grooves of the disks. 5 The upper drum 98, however, is connected to the spring 100, the other end of which is connected to the under surface of the plate 57 in an annular recess therein, as shown in Fig. 3. This spring serves as a retracting spring which will automatically rewind the rope 101 thereon when the drum 98 is released.

It should be noted that each of the rope winding drums 98 and 99 is provided with 15 a circular central opening so as to provide an open annular space or clearance for the auxiliary vertical shaft 80 to pass through the rope drums without interfering with the rotation of the latter. This arrangement enables the auxiliary shaft to be located between the bearings 79 and 82 and the use of the pinion 104 meshing with the internal annular gear 103 of the rope drum 99. The rope drums may be supported by 20 the spaced apart grooved rollers, as shown in Figs. 2 and 3. It will also be seen that by reason of the fact that the drums are in reality rings with circular openings therethrough, the clutch element 51 may be located on the vertical drive shaft 24 within the lower drum, and the circular bearing plate 59 together with part of the horizontal support or partition, may be located 25 within the space of the upper drum 98, thereby affording a very compact arrangement for the feeding and retarding mechanism, while at the same time providing means for transmitting power at will to the cutter-chain of the horizontal under-cutting 30 kerf-cutter.

The rope 101 is a comparatively light one, but of sufficient strength to perform its function. The rope 102 on the drum 99 is a comparatively heavy rope as it must be 45 much stronger to perform its function than the rope 101. One end of the rope 101 is securely fastened to the drum 98, and likewise one end of the rope 102 is securely fastened to the drum 99. On the inner annular surface of the drum 99 is an internal gear 103 with which meshes the pinion 104 which is keyed to the lower portion of the vertical shaft 80. Therefore, whenever the electric motor 30 rotates the vertical shaft 50 80, the pinion 104 will transmit motion to the drum 103 either very slowly or more rapidly, depending in which direction the plate 59 has been shifted, that is, whether the worm 69 or the worm 77 has been brought 55 into mesh with the worm wheel 81. The drum 98, however, being in no way connected to the gearing, is never positively driven by the motor under the usual conditions of operation. The rope 101 on the 60 drum 98 may be pulled manually to wind

up the spring 100, but under some conditions the spring may be wound up indirectly by the motor as when the end of the rope 101 is held fixed in a certain position, and the entire mining machine is 70 moved bodily. By means of the modification shown in Fig. 17, the rope 101 may be rewound directly and positively as the keys 142, 142 lock the drums 98 and 99 together. Preferably, a number of opposed key-ways 75 are provided on and between the flanges of the drums 98 and 99 so as to facilitate the locking together of the drums at the most convenient point.

It should be particularly observed that the 80 rope drums are of comparatively large diameters, thus preventing the rope from being bent any more than a comparatively small amount, thereby prolonging their life considerably. By reason of the large drums 85 the ropes need not be very flexible, and consequently ropes of coarser strands may be used without danger of breaking or becoming injured. Therefore, stronger and less expensive ropes may be used which will also 90 be more durable and efficient. The rope drums are initially in such position that the ropes are entirely wound up thereon except that the rope 102 extends to the rear as shown by the dotted lines 28 in Fig. 2, a 95 roller 104 being provided on the side of the mining machine body to direct the rope in the proper direction. This rope has a hook 25 which engages the eye 26 on the bracket 27 at the rear of the truck when 100 the mining machine is mounted on the latter.

Fig. 13 diagrammatically illustrates the manner in which the machine is unloaded from the truck. The larger rope 102 is unhooked from the eye 26 and connected at 105 25' to an anchorage near the face of the mine wall which is indicated by the dotted lines 105. Now, when the operator actuates the lever 83, the worm 69 or the worm 77 may be thrown into engagement with the 110 worm wheel 81, depending on whether the mining machine is to be unloaded quickly, or slowly and more carefully. In this connection, it should be observed that the throw of the lever 87 as indicated by the arc-shaped line 106 in Fig. 6 is such that whether the gear 77 or the gear 69 is shifted into operating relation with the worm wheel 81, the lever 87 will be thrown on dead center 115 with respect to the vertical shaft 84 and the link 88. Therefore, when the manual lever 83 has once been shifted, it may be left there without manually holding it, as the resistance or reaction on the link 88 120 cannot move the lever 87.

Assuming that the end of the rope 102 is 125 firmly anchored at 25' and the motor 30 is operating to turn the large drum 99 in the direction indicated by the arrow 107 in Fig. 13, the mining machine may be pulled off 130

the truck and moved to the place where it is to be used, provided the machine is properly guided. Since the pulling occurs tangentially of the drum 99, the tendency might be 5 for the machine to turn about and not be moved directly forward in the path indicated by the arrow 108. Therefore, in order to assure the movement of the machine forward in the straight path indicated by the 10 arrow 108, I have provided a rope guiding attachment which is shown in Fig. 9. This rope guiding attachment comprises a hook 109 which is adapted to be inserted in suitable openings provided therefor. On the 15 flat bar 110 extending from the hook 109 is a pulley block 111 carrying a pulley 112. The pulley block 111 fits over the bar 110 and is slideable along the same to various positions over the holes 113 therein into 20 which can be inserted the pin 114 which also extends through holes in the pulley block. By this construction, the pulley block may be held in an adjusted position on the bar 110 as may be desired under different conditions. 25

In Fig. 2 the adjustable rope pulley guide is shown in full lines at the rear portion of the machine and the hook 109 extends through suitable openings 115 (Fig. 3) in 30 the side wall of the rear portion of the frame-work of the machine. In Fig. 2 the rope pulley guide is also shown in dotted lines at the front portion of the machine. It is shown in dotted lines as being hooked 35 to the outer end of the tongue 34 just back of the cross piece 40 in the opening 115' which is shown also in Fig. 14. In Fig. 13, the rope pulley guide is shown connected in the opening 115' to the outer end of the cutter chain frame support. It will now be 40 evident that when the motor is operated to wind the rope 102 onto the drum 99 under the conditions represented in Fig. 13, the tendency for the machine to turn about while 45 being unloaded from the truck and moved to the wall of the mine will be counteracted by the rope pulley guide and the result will be that the machine will move forward in a straight path indicated by the arrow 108. 50

When the mining machine is to be pulled back onto the truck, the hook 25 is connected to the eye 26 and the freely detachable rope pulley guide 110 is connected to the frame-work or supporting frame of the mining 55 machine by extending the hook 109 through the openings 115 shown in Fig. 3. The rope pulley guide 110 will then be associated with the rope 102 at a point intermediate the periphery of the winding drum 99 and the 60 anchorage 26, as illustrated in Fig. 11, particularly when the mining machine is provided with a supporting frame which is entirely open at the sides, as shown in Fig. 1. When the drum 99 is rotated in the direction indicated by the arrow 116 in Fig. 11, a pull 65

is exerted on the rope 102, and if the mining machine is angularly disposed on the floor the location of the rope pulley guide 110 will cause the mining machine to swerve about until the rope between the drum 99 70 and the anchorage 26 becomes approximately straight, after which the rope pulley guide 110 will travel along the rope 102 so as to move the mining machine approximately rectilinearly and longitudinally of the mining machine toward the rear thereof. It should be noted that the direction of rotation of the drum 99, as illustrated in Fig. 11, when the mining machine is to be moved rearwardly, is the same as illustrated in 80 Fig. 13 when the mining machine is to be moved forwardly. It will also be seen by referring to Figs. 10 and 12 that the drum 99 rotates in the same direction as in Fig. 11, when the mining machine is to be fed for 85 a sumping cut, as illustrated in Fig. 12, or for a cut across the mine wall, as shown in Fig. 10. The reason that the same direction of rotation of the winding drum 99 may be maintained for the various operations 90 referred to, is that this winding drum is approximately of the same diameter as the width of the mining machine supporting frame with the upright axis of rotation of the drum midway between the sides of the 95 mining machine. This arrangement enables the rope 102 to be tangential with the winding drum 99, both when it extends forwardly from the side of the machine, as shown in Fig. 13, and when it extends rearwardly from the side of the machine, as shown in Fig. 11. As to the other drum 98, the same is true when the latter is positively driven by being keyed to the drum 99. However, the large diameter of the retard- 100 ing drum 98 greatly widens the range of the anchorage to which the rope 101 can be connected, because this rope, on account of the large diameter of the drum 98, can be connected to an anchorage directly back of the left-hand side of the machine, as viewed 105 in Fig. 12, or to an anchorage at any place spaced from the left-hand side of the machine to a position diagonally spaced from the forward portion of the frame. Furthermore, the rope 101, as shown in Fig. 10, may be connected to anchorages over a considerable range on the other side of the mining machine from a position directly forward of the right-hand side of the machine to a 110 position diagonally spaced from the right-hand rear portion of the machine, particularly when the sides of the main frame are entirely open, as shown in Fig. 1.

Fig. 12 represents diagrammatically one 115 way in which the cutting operation of the mining machine may be started. The heavy rope 102 is anchored at 117 near one end of the wall of the coal that is to be cut. The lighter rope 101 is anchored at 118 near the 120

other end of the wall. Now, when the lever 83 is actuated to throw the worm 77 into mesh with the worm gear 81, the vertical shaft 80 and consequently also the large 5 drum 99 will be rotated very slowly to very gradually wind up the rope 102 in the direction of the arrow 119. The operator also actuates the lever 55 to throw in the clutch 51 and thus secure rotation of the sprocket 10 50 and the movement of the chain cutter in the direction of the arrow 120 in Fig. 12.

It is preferable to hold the drum 98 in fixed position when starting the cutting operation, as diagrammatically illustrated in 15 Fig. 12. I have, therefore, provided a brake for the drum 98 to hold it in position after the rope 101 has been anchored at 118 and the spring 100 has taken all slack out 20 of the same. This brake mechanism is illustrated in Fig. 1 and comprises a brake shoe 120 adapted to engage the peripheral surface of the drum 98. This brake shoe is brought into engagement with the drum 98 by actuating the eccentric 181 at the lower 25 end of the vertical rock shaft 121 by means of the lever 140. The vertical rock shaft 121 is mounted in the bearings 122 and 123, the latter being mounted on the fixed bracket 124.

30 Fig. 10 illustrates the location of the ropes when a cut is being made by the machine along the face of the wall of the mine. During this cutting operation the mining machine remains substantially perpendicular to the wall of the mine, that is, in the relative position illustrated in Fig. 10. As soon as the cut into the wall of the mine has been well started, or when the cutter has been inserted as far as it will go, the 35 40 brake lever 140 is actuated to release the brake, and the lighter rope 101 is disconnected from its anchorage 118 and anchored at 117 instead. The heavier rope 102 is disconnected from the anchorage 117 and anchored at 118. It will, therefore, be seen that the ropes are interchanged with respect to their anchorages. The machine should move sidewise in the direction of the arrow 125 in Fig. 10. The electric motor is operated in such direction that, when the clutch 51 is thrown in, the cutter chain will be moved in the direction of the arrow 126 of Fig. 10. By actuating the lever 83, the slow gearing may be thrown in and locked 55 in place by the dead center arrangement of the lever 87. The large drum 99 will then be rotated in the direction of the arrow 127. It will thus be seen that the large drum 99, carrying the heavier rope, is always 60 operated in a clockwise direction when viewed in plan. This is true whether the mining machine is being pulled onto the truck or off the truck, or is making the cutting operation illustrated in Fig. 12, or that 65 illustrated in Fig. 10. The motor controller

box 33 may, however, be provided with reversing mechanism 138, which is desirable for moving the truck in either direction, and also under such conditions where it may be desirable to positively unwind the rope 70 102 so that this will not have to be done manually.

It should be observed that when the cutting operation illustrated in Fig. 10 is being performed, it is preferable to keep the 75 brake mechanism for the drum 98 partially applied to permit slipping while maintaining the body of the machine perpendicular to the wall of the mine. By this operation, the periphery of the drum 98 will constantly 80 slip under the brake shoe 120. Or, if desired, the brake may be firmly applied until the forward portion of the machine skews to a certain extent to the left, as viewed in Fig. 10, after which the brake may be entirely released until the rear portion of the machine skews a certain extent to the left. This operation would cause the machine to slide over the floor of the mine in zig-zag 85 90 fashion.

The rope 101 will gradually unwind from the drum 98 as the mining machine progresses along the wall of the mine. The pull exerted on the rope 102 tends to skew the rear end of the mining machine in the 95 direction in which the cut is being made, that is, to the left as viewed in Fig. 10. This is because of the resistance that the cutters meet when they strike the coal. The coal acts as fulcrum as would be evident if 100 the cutter chain were not operated at all while the rope 102 would be gradually wound on the large drum 99. Therefore, in order to prevent this tendency of the rear end of the machine to skew in the direction 105 of the cut, the rope 101 acting on the other side of the drum 98 constantly pulls the rear end of the machine in the opposite direction; the large drum 98 increases the leverage for this purpose. The adjustment is 110 such that the tendency for the rear portion of the machine to skew is counteracted by the pull on the rope 101, and therefore the cutters are maintained in proper position 115 and the machine as a whole is moved gradually to the left approximately rectilinearly, as indicated by the arrow 125 in Fig. 10. In some instances, where the drag of the bottom of the rear portion of the machine on the mine floor is sufficient, the brake 120 mechanism and the rope 101 need not be used.

When desired, instead of depending upon the spring 100 for rewinding the rope 101 on the drum 98, manual mechanism may be 125 employed as illustrated in Fig. 7. As there illustrated, a crank 128 supported by the plate 57 carries a pinion 129 which meshes with the internal annular gear on the peripheral flange of the drum 98. It is evident 130

that this crank may be rotated in either direction to wind or unwind the rope 101, and, after it is anchored, to take the slack out of the same. After the rope is adjusted 5 to a proper position, the brake mechanism operated by lever 140 may be depended upon to hold the drum 98 stationary.

After the machine has completed the cut in the manner illustrated in Fig. 10, the 10 lever 83 may be moved to reverse position so as to change the gearing to fast feed. This is done by moving the worm 69 into engagement with the worm wheel 81 and locking it in place by the lever 87 passing 15 through or beyond the dead center. If desired, the mining machine may be moved to a new location by means of the heavy rope and its drum mechanism.

It will thus be seen that the heavy rope is 20 depended upon to pull the machine from place to place, and the lighter rope is depended upon to properly guide the machine. It should be observed that when the machine is being moved to a new location and 25 no cutting operation is taking place, the machine is moved rapidly so as not to cause any waste of time; the clutch 51 is thrown out at such time to save power. If desired, after the cut across the wall of the mine is 30 made, the machine may be loaded on the truck as illustrated in Fig. 11 and taken to another part of the mine.

In order to protect the ropes at the points 35 where they emerge from the main frame of the machine when the ropes are anchored at various angles to suit different conditions of operation, guide rollers are provided, as shown in Figs. 14, 15 and 16. The lighter rope 101 emerges from the frame of the machine to the opening 132 and then passes 40 over the guide roller 133, which is journaled in bearings extending from the lateral face of the mining machine frame. The rope 101 may, therefore, be inclined in various 45 directions without coming in contact with the frame of the machine. When the rope 101 is permitted to recede into the shell or frame of the mining machine and is then anchored on the other side of the machine, 50 it will extend over and be guided by the roller 104, as shown in dotted lines in Fig. 14. The heavy rope 102 passes over a 55 guide pulley 136 when it emerges from the front portion of the machine, although the frame of the machine is entirely open at that point. Such a guide pulley on the frame of the machine is unnecessary when the machine is being pulled directly forward, as illustrated in Fig. 13. When the 60 machine is being operated under the conditions of Fig. 12, however, and the machine is being skewed about to a position perpendicular to the wall of the mine and with a cutter fully inserted, the roller 136 is depended upon to properly guide the heavier 65

rope and prevent its being injured by the frame of the machine. When the conditions shown in Fig. 10 obtain, the lighter rope 101 will be guided over the pulley or roller 133, as shown in Figs. 14, 15 and 16. Under 70 these conditions the heavier rope will be guided over the pulley or roller 137, as shown in Fig. 15. When the frame of the mining machine is entirely open at the sides, as shown in Fig. 1, the guiding pulleys 75 104, 133, 136 and 137 may be dispensed with, except that shown in Fig. 9.

After the mining machine has been replaced on the truck and the socket 23 brought immediately above the clutch coupling pin 80 13, the motor may be operated to effect transportation of the mining machine to another part of the mine. The means for securing positive actuation in the same direction of both axles 18, 18' is shown diagrammatically 85 in Fig. 5, which is a plan view of the truck gearing. The worm 9 which carries the square pin 13 meshes with the worm wheel 8 which is shown in dotted lines in Fig. 3, back of the worm 9. When motion is given 90 to the shaft 7 which is mounted in the bearings 10, 10', the bevel gear 6, 6' will be rotated, and, since they are in mesh with the bevel gears 5, 5', the axles 18, 18' will both be rotated. If a motion is given to the 95 shaft 7 in the direction indicated by the arrow thereon, the axles 18, 18' will be rotated in the directions indicated by the arrows on the latter and the truck will be moved forward. A reverse rotation of the shaft 7, by 100 reversing the electric motor 30, will effect a rearward movement of the truck and the mining machine thereon.

Having thus described my invention by setting forth an embodiment thereof, what 105 I claim and desire to have secured by Letters Patent of the United States is:—

1. The combination with a mining machine, of feeding mechanism therefor comprising a rope drum and a rope connected thereto, a freely detachable rope pulley guide adapted to be hooked to various parts of the frame of said mining machine, and power mechanism for operating said feeding mechanism to effect longitudinal 110 bodily movement of said mining machine when said rope passes through said pulley guide and its free end is anchored at a distance from said mining machine.

2. The combination with a mining machine, of rope-winding apparatus connected thereto, a rope connected to said winding apparatus, and a freely detachable rope guiding device adapted to be detachably hooked to the rear portion of the frame of 125 said mining machine to effect bodily movement thereof longitudinally off from a mine car when the free end of said rope is anchored in the mine and said winding apparatus is operated, said rope-guiding device 130

being adapted to be detachably hooked also to the forward portion of the frame of said mining machine to effect bodily movement thereof longitudinally onto the mine car 5 when the free end of said rope is anchored on the mine car and said winding apparatus is operated.

3. The combination with a mining machine, of propelling apparatus mounted 10 thereon comprising a horizontal rope winding drum having a large diameter approximately equal to the width of said mining machine and a rope connected to said winding drum and wound thereon, and a freely 15 detachable rope-guiding device adapted to be connected to various portions of said mining machine to guide the rope when the free end of said rope is anchored and said winding apparatus is operated.

20 4. The combination with a mining machine, of a truck for carrying the same, an anchorage at the rear end of one side of said truck, winding apparatus mounted on said mining machine and comprising a rope 25 winding drum having a large diameter approximately equal to the width of said mining machine and with its peripheral edge traveling at the sides of said mining machine, said winding apparatus also comprising 30 a rope connected to said drum and wound thereon with its free end adapted to be connected to said anchorage, and a freely 35 detachable rope guide connected to the rear portion of said mining machine to effect longitudinal travel of said mining machine onto said truck when said mining machine is operated while said rope guide engages the straight taut portion of said rope extending from said drum along one side of said mining 40 machine to said anchorage.

5. The combination of a mining machine, a truck for carrying the same, an anchorage on said truck, winding apparatus comprising 45 a rope drum mounted on said mining machine and having a large diameter approximately equal to the width thereof and a rope connected to said drum and wound thereon, its free end being connected to said anchorage, and a freely 50 detachable rope guiding device hooked to the rear portion of said mining machine and associated with said rope between said drum and said anchorage to effect the movement of the mining machine in an approximately direct line 55 onto said truck when said winding apparatus is operated.

6. The combination with a mining machine, of winding mechanism mounted thereon comprising a rope drum of a large diameter approximately equal to the width of 60 said mining machine and a rope connected to and wound on said drum, and a rope guiding device connected to said mining machine quickly detachable manually but when 65 in position being associated with said rope

to swerve the mining machine into a path of travel parallel to the rope between said rope-guiding device and the anchorage to which the free end of said rope is connected.

7. The combination with a mining machine, of a rope drum mounted thereon having a large diameter approximately equal to the width of said mining machine, power mechanism for operating said drum, a rope connected to said drum and wound thereon 75 and having its free end adapted to be connected to an anchorage at a distance from said mining machine, and a single rope-guiding device detachably and loosely mounted on said mining machine and extending 80 therefrom to co-act with said rope to effect a sidewise pull on a portion of said mining machine to automatically swing the latter to a longitudinal path of travel when the outer 85 end of said rope is anchored and said power mechanism operates said drum.

8. The combination with a mining machine, of feeding mechanism therefor comprising a rope drum, a rope connected to and wound on said rope drum, power mechanism 90 for operating said rope drum, rope winding mechanism comprising a rope drum and a rope connected thereto and wound thereon, the free end of said first-named rope being adapted to be connected to an anchorage 95 opposite one side of said mining machine and the free end of the other rope being adapted to be connected to an anchorage opposite the other side of said mining machine, and a spring acting on said rope drum 100 winding mechanism to automatically re-wind its rope drum when its rope is released from its anchorage.

9. The combination with a mining machine, of means for exerting a pull on said 105 mining machine at an intermediate portion thereof to feed the same laterally, a rope drum device for retarding the rear portion of said mining machine during its feeding operation, said rope drum device comprising 110 a rope drum and a rope connected thereto, wound thereon, and having its free end adapted to be connected to an anchorage at a distance from said mining machine, a brake acting on said rope drum to regulate such 115 retardation and thereby control the lateral feeding of said mining machine, and a spring for re-winding the rope on said rope drum.

10. The combination with a mining machine, of feeding mechanism therefor, a horizontal support in said mining machine, grooved rollers carried by said support, a rope drum device, an internal annular flange on sand drum device and fitting into the grooves of said rollers so as to be supported 120 rotatively thereby, and means for controlling the operation of said rope drum device as to winding and rewinding.

11. The combination with a mining machine, of feeding mechanism therefor, a hori- 130

- zontal support on said mining machine, a horizontal drum of diameter approximately equal to the internal width of said mining machine, grooved rollers carried by said 5 horizontal support, and an internal annular flange on said drum and fitting into the grooves of said rollers for rotative support thereby.
12. The combination with a mining machine, of a horizontal support therein, grooved rollers carried by said support, a feeding device for the mining machine comprising a rope drum, and a flange on said drum and fitting in the grooves of said rollers for rotative support.
13. The combination with a mining machine, of feeding mechanism therefor comprising a rope drum and a rope connected thereto and wound thereon and having its 20 free end adapted to be connected to an anchorage in the mine, an additional rope drum and a rope connected thereto and wound thereon and having its free end adapted to be connected to another anchorage 25 in the mine, said additional rope drum being mounted independently of said first named rope drum, means for controlling the rotation of said additional rope drum independently of said first named rope drum 30 to secure lateral feeding motion of said mining machine during the operation thereof and during the operation of said feeding mechanism, and a spring connected to said additional drum to automatically rewind 35 the rope thereon when released from its anchorage.
14. The combination with a mining machine, of feeding mechanism therefor comprising a horizontal rope drum of a large 40 diameter approximately equal to the width of said mining machine, an additional horizontal rope drum of approximately the same large diameter as that of said first named rope drum, and a spring connected to said 45 additional rope drum tending to rewind the rope extending therefrom.
15. The combination with a mining machine, of feeding apparatus therefor comprising a rope drum of a diameter approximately 50 equal to the width of said mining machine, a rope connected to said rope drum, power mechanism for operating said feeding apparatus, retarding mechanism comprising an additional rope drum of equal 55 diameter separate from said power mechanism and mounted concentrically with said first-named rope drum but for rotation independently thereof, a rope connected to said additional rope drum and wound thereon and 60 extended therefrom to an anchorage in the mine, and a key fitting in opposing recesses in the peripheral portions of said drums for compelling their simultaneous rotation.
16. The combination with a mining ma-
- chine, of a horizontal rope drum mounted 65 thereon, a rope connected to said rope drum and wound thereon and extending directly therefrom to an anchorage in the mine, an additional rope drum, an additional rope connected to said additional rope drum and 70 wound thereon and extending directly therefrom to another anchorage in the mine, means for positively rotating one of said drums while the other drum remains free of such means, and a spring for retarding 75 the unwinding of the rope from such other drum.
17. The combination with a mining machine, of feeding mechanism therefor comprising a rope drum and a rope connected 80 thereto and wound thereon and its free end adapted to be connected to an anchorage in the mine, retarding mechanism comprising an additional rope drum and a rope connected to said additional rope drum and 85 wound thereon and having its free end adapted to be connected to another anchorage in the mine, a brake acting on said additional rope drum to control the retardation of said retarding mechanism during 90 the operation of said feeding mechanism, and locking mechanism for connecting said rope drums to effect the positive actuation of said additional rope drum to return the mining machine toward initial position when 95 said first named rope is released from its anchorage and the feeding mechanism continued in operation.
18. The combination with a mining machine, of feeding mechanism therefor comprising a rope winding drum, retarding mechanism comprising an additional rope winding drum, and a radial key engaging the peripheral portions of said drums for locking the same to rotate together.
19. The combination with a mining machine, of feeding mechanism therefor comprising a horizontal rope winding drum of a diameter substantially equal to the width of the mining machine, means for positively 110 driving said drum, another rope winding drum of substantially the same diameter as the first named drum and mounted on said mining machine concentric therewith, a spring for retracting the said other drum, a 115 brake associated with said other drum to control the rotation thereof against the action of said spring when the feeding mechanism is operated, and a locking device between said drums to secure positive rotation 120 of the said other drum.
20. The combination with a mining machine comprising cutting mechanism and a power driven shaft connected to said cutting mechanism, of feeding apparatus comprising a rope drum concentric with said shaft and approximately equal in diameter to the width of said mining machine, a rope con-

nected to said drum and wound thereon and adapted to extend laterally from said drum or along either side of said mining machine from the periphery of said drum, a second 5 rope drum concentric with said shaft and also of a diameter approximately equal to the width of the mining machine, an additional rope connected to said second rope drum to be wound thereon and extend from 10 the periphery thereof along one side of said mining machine, and retarding mechanism applied to said second rope drum.

21. The combination with a mining machine comprising cutting mechanism and a 15 vertical power driven shaft connected to said cutting mechanism, of feeding apparatus comprising a rope drum of large diameter approximately equal to the width of the frame of said mining machine and mounted 20 concentrically with said shaft, a rope wound on said drum and extending rearwardly along one side of said mining machine frame to an anchorage when said mining machine is to be shifted rearwardly, said rope being 25 also adapted to extend forwardly along the other side of said mining machine frame to an anchorage when said mining machine is to be shifted forwardly, said rope being also adapted to extend laterally from said mining 30 machine frame to an anchorage when the mining machine is to be fed laterally, guiding mechanism comprising an additional rope drum of a diameter approximately equal to the width of the frame of 35 said mining machine and also mounted concentrically with said shaft, an additional rope wound on said additional rope drum and adapted to extend from said mining machine frame to an anchorage during feeding 40 operations and also during shifting of the mining machine longitudinally forwardly and rearwardly, retarding mechanism applied to said additional rope drum, and means for connecting said rope drums to rotate together and effect transmission of 45 power from said shaft to said additional rope drum.

22. In a mining machine, the combination with a supporting frame, of a chain cutter 50 mounted thereon in position to cut a horizontal kerf in a mine wall, a vertical drive shaft connected to said chain cutter, a motor connected to said drive shaft, a rope drum mounted concentrically with said drive 55 shaft, mechanism for transmitting power from said motor to said rope drum to rotate the latter, a rope wound on said drum and adapted to have its free end connected to an anchorage, a second rope drum also concentric with said shaft, an additional rope wound 60 on said second rope drum and having its free end adapted to be secured to an anchorage, retarding mechanism applied to said second rope drum, and means for connecting said

first named drum to said second drum to 65 secure transmission of power from said motor to said second drum.

23. In a mining machine, the combination with a supporting frame, of a chain cutter mounted thereon and comprising a sprocket 70 wheel, a vertical drive shaft connected to said sprocket wheel, a motor connected to said drive shaft, a clutch for connecting said drive shaft to said sprocket wheel to drive said chain cutter, a rotatable drum mounted 75 on said frame concentrically with the drive shaft, an inner annular gear on said drum spaced from said drive shaft, mechanism for transmitting power from the motor to said rope drum to rotate the same, means for 80 controlling said power transmitting mechanism to effect the rotation of said drum independently of the operation of said chain cutter, and a rope mounted on said drum and having its free end adapted to be secured to 85 an anchorage.

24. In a mining machine, the combination with a supporting frame, of horizontal kerf cutting mechanism mounted thereon and comprising a sprocket wheel, a vertical drive 90 shaft extending through the center of said sprocket wheel, a motor connected to said vertical drive shaft, a clutch for connecting said drive shaft to said sprocket wheel to drive said kerf cutting machine, an annular rope drum mounted on said frame concentrically with said vertical drive shaft and spaced from said drive shaft to leave an open central portion surrounding said vertical drive shaft, an additional vertical 95 drive shaft mounted on said frame eccentrically relatively to said rope drum and extending through the open central portion thereof, an inner annular gear on said rope drum, a pinion on said eccentric drive shaft 100 and meshing with said inner annular gear, mechanism for transmitting power to said eccentric drive shaft to effect the rotation of said rope drum, and a rope wound on said rope drum and having its free end adapted 105 to be connected to a fixed point.

25. The combination with a mining machine including horizontal kerf-cutting machine, of feeding mechanism therefor, a horizontal support in said mining machine, 115 grooved rollers carried by said support, a rope drum retarding device, means for controlling the operation of said rope drum retarding device, and means co-acting with said groove devices for supporting the feeding mechanism and said rope drum retarding device.

26. The combination with a mining machine, of feeding mechanism therefor, a horizontal support in said mining machine, 120 a retarding device for the feeding mechanism comprising a horizontal rope drum of a diameter approximately equal to the width 125

- of the frame of said mining machine, grooved rollers carried by said horizontal support, and an internal annular flange on said drum and fitting said grooved rollers 5 for rotative support thereby.
27. The combination with a mining machine comprising cutting mechanism and a power driven shaft connected to said cutting mechanism, of feeding apparatus comprising a rope drum concentric with said shaft, a motor, gearing connected between said motor and said rope drum comprising an internal annular gear on said rope drum, and retarding mechanism also comprising a 10 rope drum concentric with said shaft.
28. In a mining machine, the combination with a supporting frame, of a vertical power driven shaft extending through the bottom thereof, cutting mechanism comprising a 15 sprocket wheel mounted concentrically with said shaft, feeding mechanism comprising an annular rope drum mounted on said frame concentrically with said power driven shaft with an open space between the inner 20 periphery of the said annular drum and said vertical shaft, a rope connected to said drum and wound thereon and having its free end adapted to be connected to an anchorage in a mine, means for rotating said 25 shaft, a clutch on said shaft in the open annular space between said shaft and said annular drum for connecting said shaft to said sprocket wheel to drive said cutting mechanism, means for transmitting power 30 to said rope drum to rotate the latter relatively to said frame around said vertical shaft, and means for controlling said feeding mechanism.
29. The combination with a mining machine comprising cutting mechanism, of feeding mechanism for said mining machine comprising a rope drum having a 35 diameter approximately equal to the width of said mining machine, a rope wound on 40 said drum and adapted to extend therefrom forwardly from one side of the mining machine or rearwardly along the other side of said machine or laterally to anchorages located respectively forwardly, rearwardly or 45 laterally of said mining machine, and rope guiding mechanism connected to the forward portion or the rear portion of said mining machine in position to engage the rope between its anchorage and said rope 50 drum to effect movement of the mining machine longitudinally toward the forward anchorage or toward the rearward anchorage while said rope extends directly from either 55 side of said mining machine to such forward 60 or rearward anchorage.
30. The combination with a mining machine comprising an elongated cutter-bar and an endless cutter-chain mounted to travel around said cutter-bar, of a rope drum 65 mounted on said mining machine on an up-

right axis with its periphery movable adjacent one side of said mining machine, a freely detachable rope guiding device connected to the forward portion of said cutter-bar, a rope wound on said drum and extending 70 from the periphery thereof at one side of said mining machine along one side of said cutter-bar to an anchorage with the intermediate portion of said rope in engagement with said rope guiding device, and 75 means for rotating said rope drum on said upright axis to effect a pull on said rope and movement of the mining machine approximately longitudinally of the cutter-bar, while said rope guiding device by engagement 80 with the taut rope compels the mining machine to be moved thus longitudinally.

31. The combination with a mining machine comprising an elongated cutter-bar 85 and an endless cutter-chain traveling around said cutter-bar, of a rope drum having a diameter approximately equal to the width of the mining machine and mounted to rotate on an upright axis midway between 90 the sides of the mining machine, a freely detachable rope guiding device adapted to be connected to the outer portion of said cutter-bar at one side of the mining machine or to the rear portion of said mining machine at the other side thereof, a rope wound 95 on said drum and adapted to be connected to an anchorage forwardly of the mining machine or rearwardly thereof, and means for operating said rope drum to exert a 100 pull on said rope while said rope guiding device engages said rope at a point intermediate said rope drum and either of said anchorages to cause the mining machine to be moved approximately along a direction 105 longitudinally of said cutter-bar and toward either of said anchorages.

32. The combination of a mining machine, and feeding mechanism therefor comprising a support on said mining machine, grooved 110 rollers carried by said support, a rope drum having an internal annular flange fitting into the grooves of said rollers so as to be supported rotatively thereby, a rope wound on said drum and having its free end adapted 115 to be connected to a fixed point, and means for operating said rope drum.

33. The combination of a mining machine, and feeding mechanism therefor comprising a support on the frame of said 120 mining machine, a rope drum of a diameter approximately equal to the width of the frame of said mining machine, grooved rollers carried by said support, means on said drum fitting into the grooves of said 130 rollers for rotative support thereby, a rope wound on said drum and having its free end adapted to be connected to a fixed point, and means for operating said rope drum.

34. The combination of a mining machine, and means for shifting the position of said mining machine comprising a ring rope drum having an internal annular flange, a plurality of circumferentially spaced apart, circumferentially grooved rollers mounted in the mining machine frame for rotation about upright axes in position to rotatively support said ring drum by the said flange fitting into the roller groove, a rope wound on said drum and having its free end adapted to be connected to an anchorage, an internal annular gear on said ring drum, and means connected to said gear to drive said drum to exert a pull on said rope to effect shifting of the mining machine. 80
35. The combination with a mining machine, of a rope drum, means for rotatively supporting said rope drum in the mining machine frame at spaced apart points adjacent the peripheral portion of said rope drum, and a rope wound on said drum and having its free end adapted to be connected to an anchorage in a mine. 85
36. The combination with a mining machine, of feeding apparatus therefor comprising a horizontal rope drum of a diameter approximately equal to the width of the mining machine frame, a rope wound on said drum and having its free end adapted to be connected to an anchorage, power mechanism for rotating said drum relatively to the mining machine frame to exert a pull on said rope and shift the position of the mining machine, retarding mechanism comprising an additional horizontal rope drum of approximately equal diameter separate from said power mechanism and mounted concentrically with said first named rope drum but for rotation independently thereof, a rope wound on said additional rope drum and having its free end adapted to be connected to an anchorage in the mine, the respective ropes being extended out of alinement with each other to the said anchorages, and means for locking said drums together to compel their simultaneous rotation. 95
37. The combination of a mining machine and feeding mechanism therefor comprising a horizontal ring rope drum of a diameter approximately equal to the width of the mining machine, an additional horizontal ring rope drum also of a diameter approximately equal to the width of the mining machine frame, means for circumferentially supporting said ring rope drums concentric with each other and each for rotative movement relatively to the mining machine frame independently of each other, means for positively driving the first named rope drum, means for retracting the said additional rope drum, a rope wound on said first named rope drum and having its free end adapted to be connected to an anchorage in a mine 100
38. The combination of a mining machine comprising cutting mechanism and a power driven shaft connected to said cutting mechanism, feeding apparatus comprising a rope drum mounted on the mining machine frame for rotation relatively thereto, a motor, gearing connected between said motor and said rope drum comprising an internal annular gear on said rope drum, retarding mechanism also comprising a rope drum mounted on said mining machine frame for rotative movement relative thereto, a rope wound on said first named rope drum and having its free end adapted to be connected to an anchorage in the mine, and an additional rope wound on the retarding rope drum and having its free end adapted to be connected to another anchorage, said ropes being out of alinement with each other during the shifting of the position of the mining machine to feed the latter. 105
39. The combination of a mining machine comprising cutting mechanism and a power driven shaft connected to said cutting mechanism, feeding apparatus comprising a rope drum surrounding said shaft, a motor, gearing connected between said motor and said rope drum comprising an internal annular gear on said rope drum, and retarding mechanism also comprising a rope drum surrounding said shaft. 110
40. The combination of a mining machine comprising cutting mechanism and an upright power driven shaft adapted to be connected to said cutting mechanism, feeding apparatus comprising a horizontal ring rope drum surrounding said upright shaft, a motor, gearing connected between said motor and said ring rope drum comprising an internal annular gear on said ring rope drum, and retarding mechanism also comprising a horizontal ring rope drum surrounding said upright shaft. 115
41. The combination of a mining machine comprising horizontal kerf cutting mechanism and an upright power driven shaft adapted to be connected to said kerf cutting mechanism to drive the latter, feeding apparatus comprising a horizontal ring rope drum surrounding said shaft and spaced 120
- 125
- 130

- therefrom, retarding mechanism comprising an additional horizontal ring rope drum surrounding said upright shaft and spaced therefrom, means for circumferentially supporting said ring rope drums on the mining machine frame for rotative movement relatively to said frame, power transmission mechanism comprising an auxiliary upright shaft spaced from said upright power driven shaft and extending through said ring drums and connected to an internal annular gear on the first named drum, and two ropes one wound on each of said drums and adapted to have their free ends connected to anchorages in the mine in positions where said ropes will be out of alignment with each other during the operation of said mining machine, including the feed thereof by shifting the position of the mining machine when said first named rope drum is driven while said retarding mechanism is effective.
42. The combination of a mining machine comprising under-cutting mechanism, feeding mechanism, for said mining machine comprising a ring rope drum, means for supporting said rope drum circumferentially in the frame of the mining machine in an approximately horizontal plane relatively low and immediately above said under-cutting mechanism and having a peripheral travel at one side of the mining machine, a draft rope wound on said drum and adapted to extend tangentially therefrom along one side of said under-cutting mechanism parallel to the longitudinal upright plane extending through the mining machine, and a rope guide adapted to be connected temporarily to the forward portion of the under-cutting mechanism and engage said draft rope at a point between said rope drum and an anchorage to which the free end of said rope is connected.
43. The combination with a mining machine comprising an under-cutting kerf cutter extending longitudinally of the mining machine frame, of draft mechanism mounted on said mining machine frame and comprising a large ring rope drum having a diameter approximately equal to the width of said mining machine frame, means for circumferentially supporting said rope drum on said frame in a relatively low horizontal plane adjacent the horizontal plane of said kerf cutter, a draft rope wound on said drum and adapted to extend therefrom tangentially forwardly or rearwardly along either side of the mining machine parallel to the length thereof, the free end of said rope being adapted to be connected to a fixed point external of the said mining machine, rope guiding mechanism adapted to be connected with said rope at a point intermediate said rope drum and said fixed point on either side of the mining machine, and means for rotating said drum to effect

longitudinal movement of said mining machine in either direction when said rope is thus associated with said rope guiding mechanism.

44. The combination with a mining machine comprising an under-cutting kerf cutter, of a horizontal rope drum mounted in the frame of said mining frame in a relatively low plane adjacent the plane of said kerf cutter and having a diameter approximately equal to the width of said mining machine frame with the peripheral paths of travel adjacent the open sides of said frame, a draft rope wound on said drum and adapted to extend therefrom at either side of the mining machine frame to anchorages extending over a range of approximately ninety degrees from a position extending from an anchorage to the rope drum at right angles with the mining machine frame to an anchorage extending to the rope drum in alignment with the side of the mining machine, and means for rotating said drum to exert a pull on said rope to propel the mining machine laterally, forwardly, rearwardly or angularly, in accordance with the relative position of the anchorage.

45. The combination with a mining machine comprising an elongated horizontal kerf cutter, of a horizontal rope drum mounted on said mining machine for rotation on an upright axis midway between the sides of the frame of said mining machine, said rope drum having a diameter approximately equal to the width of the said frame, a draft rope wound on said drum and adapted to extend from the mining machine frame on either side thereof at right angles thereto and also to anchorages in alignment with the sides of the mining machine frame and to intermediate anchorages, rope guiding mechanism connected to the mining machine in position to engage said rope intermediate the rope drum and the anchorage, and means for rotating said drum to shift the mining machine laterally when said rope extends transversely therefrom to an anchorage and to shift said mining machine longitudinally when the rope extends to an anchorage in alignment with one of the sides of the mining machine frame and when said rope guiding mechanism is associated with said rope.

46. In a mining machine, the combination with a bed frame, of a horizontal chain kerf cutter mounted on said frame and comprising a sprocket wheel, a vertical drive shaft connected to said sprocket wheel, a motor connected with said drive shaft, two rotatable drums surrounding said shaft and spaced therefrom, mechanism for transmitting the power of the motor to the inner circular portion of one of said drums to ro-

tate the same, a rope engaging the last mentioned drum, said rope being adapted to have its free end secured to a fixed point to cause bodily movement of the mining machine as the drum is rotated, a rope engaging the other drum and adapted to have its free end secured at a fixed point, and means connected with said other drum for tensioning said rope.

5 47. In a mining machine, the combination with a movable bed frame, of a horizontally projecting cutter arm rigid with the bed frame, a cutter chain supported on and guided by said cutter arm, a sprocket wheel 10 engaging the cutter chain to drive it, a vertical drive shaft connected to the sprocket wheel in axial alinement therewith, a motor connected with the drive shaft, a rotatable ring winding drum mounted for circumferential support at places spaced from said vertical drive shaft, with the periphery of said drum exposed at the sides of said bed frame along lines parallel to a vertical plane extending longitudinally through the 15 center of the mining machine, mechanism for transmitting power of the motor to rotate said drum in either direction independently of the direction of rotation of said sprocket wheel, and a feed rope engaging 20 the drum and adapted to extend therefrom directly to a fixed point external to the machine.

48. In a mining machine, the combination with a movable bed frame, of a horizontally projecting cutter arm rigid with the bed frame, a cutter chain supported on and guided by said cutter arm, a sprocket wheel 35 engaging the cutter chain to drive it, a vertical drive shaft connected to the sprocket wheel in axial alinement therewith, a motor 40 connected with the drive shaft, a rotatable winding drum mounted on said frame in a horizontal position and surrounding said vertical drive shaft, the periphery of said drum at one side of the machine being exposed along lines parallel to the direction 45 of feed, mechanism for transmitting power of the motor to rotate the drum in either direction independently of the direction of rotation of the sprocket wheel, and a feed 50 rope engaging the drum and adapted to extend therefrom at one side of the mining machine to a fixed point external thereto.

In testimony whereof I have signed my name to this specification, in the presence 55 of two subscribing witnesses, on the 5th day of February, A. D. 1918.

EDMUND C. MORGAN.
